No. 841,097.

PATENTED JAN. 15, 1907.

T. McG. AIKEN & J. E. HARMON.

ICE CREAM DIPPER.

APPLICATION FILED OCT. 3, 1906.

UNITED STATES PATENT OFFICE.

THOMAS McG. AIKEN AND JAMES E. HARMON, OF ALLEGHENY, PENNSYLVANIA.

ICE-CREAM DIPPER.

No. 841,097.

Specification of Letters Patent.

Patented Jan. 15, 1907.

Application filed October 3, 1906. Serial No. 337,182.

To all whom it may concern:

Be it known that we, THOMAS McG. AIKEN and JAMES E. HARMON, citizens of the United States, residing at Allegheny, in the county of Allegheny and State of Pennsylvania, have invented certain new and useful Improvements in Ice-Cream Dippers; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to a new, novel, and useful improvement in ice-cream dippers and molds that can be operated with one hand, and has for its primary object the construction of a device for the purpose set forth that will be simple and quick to operate, inexpensive of manufacture, and likewise be free from any unsanitary features.

In the accompanying drawings, forming a part of this specification, we have shown several detail views of our invention, Figure 1 being the complete disher in perspective. Fig. 2 is a longitudinal section of the bowl and handle portion. Fig. 3 is an end view of the spring handle portion in its normal position. Fig. 4 is a distended view of the end portion of the handle, showing relative position of the slotted openings formed therein; and Fig. 5 is a detached view of the scraping knives and shaft attached thereto.

Throughout the different views of the drawings the numeral 1 designates the bowl or mold portion of the device, which is preferably made, as shown, in a semicircular form, or it may be constructed of different shapes to suit the needs of the trade.

Formed integral with the bowl 1 is a hollow handle portion 2, having two branch or collapsible spring members 3 3, constructed for about two-thirds of the entire length of said handle. At the outer ends of these two spring members are the reduced portions 4 4, which are bent inwardly at right angles with the spring members and so arranged that they will overlap and freely pass each other when the spring portion of said handle is being compressed or relaxed. Formed adjacent the extreme outer ends of these two reduced portions 4 4 are the half-elliptical-shaped slotted openings 5 5, the arc of the

circle of said slots being reversed with relation to each other, as seen in Fig. 4 of the drawings, and midway in each of these slots, on the opposite side from the circle above referred to, are formed the small slots 6 6, the purpose of which will be more fully described farther on. Also formed in the lower right-hand and upper left-hand corners, respectively, of the two bent portions 4 4 are the oblong slots or guideways 7 7, positioned and adapted to receive the hooked lugs 8 8, formed on the extreme ends of said bent portions, which serve to limit the movement of the contracting and expanding ends of said spring-actuated handle.

Operatively seated in the bowl portion 1 are a plurality of scraping or cutting knives 9 9, made to conform to the contour of said bowl, and rigidly connected to these knives is a shaft or stem 10, which passes through the hollow portion of the handle 2 and between the spring members 3 3, extending the full length of said handle. At the extreme free end of said shaft is formed the pins or fork 12, the same being adapted to enter and seat in the slots 6 6 and operate in the elliptical slotted openings 5 5, as will be more fully set forth.

Formed at the outer junction of the scraping-knives 9 9 is a lug 13, which registers in a corresponding opening formed in the bowl and serves as a pivotal point for revolving said knives.

Assuming that all the parts have been constructed and positioned as shown in Fig. 1 of the drawings, the operator simply grasps the handle portion around the spring members 3 3 and after filling the bowl from the receptacle containing the cream, in order to release the contents therefrom onto the plate or glass provided for that purpose, simply squeezes on said spring members, thus contracting the same. This movement causes the bent members 4 4 to slide one on the other, and in doing so the pins 12 12, seated in the slots 6 6, will be drawn along the arc of the circle formed in the openings 5 5, thus rotating the shaft 10 and causing each of the knives 9 9 to describe a quarter-circle scraping movement in the bowl 1 and by so doing dislodge the cream therefrom. This operation above described is done with one hand and so rapidly that no time is lost in removing the cream from the bowl. By simply releasing the pressure on the spring handle portion the

members 33 will expand to their normal position, and in so doing the pins 12 12 will be drawn back to their normal seats, thereby reversing the shaft 10 and returning the knives 5 99 to the opposite side of the bowl.

It will be observed that our device can be constructed in two pieces and for cleaning and other purposes the knives can be removed from the bowl by simply springing 10 the pivotal lug 13 clear of the opening formed in said bowl, lifting said knives from their seat, after which the shaft 10 can be readily drawn through the hollow handle.

Having thus fully described our invention, 15 what we claim as new, and desire to secure by Letters Patent, is—

1. In combination, a bowl, a hollow handle carried thereby and communicating with the interior thereof, said handle terminating 20 in resilient sections, scraping means arranged within the bowl, a shaft engaging the scraping means and passing through the hollow handle and contacting with the resilient sections thereof.

2. In a device of the character described, a bowl, a hollow handle therefor communicating with the interior thereof, said hollow handle terminating in resilient sections having perforations, scraping means within the 30 bowl, and a shaft for the scraping means passing through the hollow handle and pins on the shaft engaging the perforations of the resilient sections.

3. In a device of the character described, a suitable bowl; a hollow handle portion connected to said bowl; parallel spring compression members formed integral with the handle portion, the ends thereof being bent inwardly at right angles with the body portion 40 and adapted to overlap and freely pass each other; scraping means seated in the bowl; a shaft connected with said means and passing through the handle portion the full length thereof, on the outer end being a fork; slotted 45 openings formed in said bent portions adapted to receive the fork formed on the end of the shaft; means for revolving said shaft; and scraping means during the process of compressing or relaxing the spring members, and 50 means for limiting the movement of the spring members; as, and for, the purpose set forth.

4. In a device of the character described, a bowl, a hollow handle therefor communicating with the interior of the bowl, scraping means within the bowl, a shaft for the scraping means passing through the hollow handle, said hollow handle terminating in resilient sections, inturned overlapping portions on the resilient sections, said inturned portions having perforations, and pins on the shaft extending within the perforations of the inturned portion. 55 60

5. In a device of the character described, a bowl, a hollow handle therefor communicating with the interior thereof scraping means within the bowl, a shaft for the scraping means passing through the hollow handle, said hollow handle terminating in resilient sections, inturned overlapping portions on 70 the resilient sections, said inturned portions having perforations, pins on the shaft extending within the perforations of the inturned portion, and guiding means for the inturned portions. 75

6. In a device of the character described, a suitable bowl; a handle secured to said bowl; scraping means seated in the bowl; a shaft secured to said scraping means and passing through the handle; spring members formed 80 in said handle the ends thereof being bent inwardly and adapted to lap over and freely pass each other; slots formed in said bent portions adapted to receive the end of the shaft and to rotate said shaft while the 85 spring members are being compressed or relaxed.

7. In combination, a bowl, a hollow handle carried thereby and communicating with the interior thereof, said handle terminating 90 in resilient sections, scraping means within the bowl, a shaft engaging the scraping means and passing through the hollow handle and contacting with the resilient sections thereof, and means whereby the movement of the 95 resilient sections rotates the shaft.

In testimony whereof we affix our signatures in presence of two witnesses.

THOMAS McG. AIKEN.
JAMES E. HARMON.
